UNITED STATES PATENT OFFICE.

NICKOLAS J. NIKS, OF KALAMAZOO, MICHIGAN.

PAPER-MAKING MACHINE.

1,327,289.

Specification of Letters Patent. Patented Jan. 6, 1920.

Application filed September 3, 1918. Serial No. 252,293.

To all whom it may concern:

Be it known that I, NICKOLAS J. NIKS, a citizen of the United States, residing at the city and county of Kalamazoo and State of Michigan, have invented certain new and useful Improvements in Paper-Making Machines, of which the following is a specification.

This invention relates to improvements in paper making machines.

The main objects of this invention are:

First, to provide an improved paper making machine well adapted for the handling of tissue and other thin papers.

Second, to provide an improved paper making machine in which the paper is carried from a couch roll to the drier on a continuous felt.

Third, to provide an improved paper making machine in which the press felt, and the press roll take off felt, which I provide, are washed during the operation of the machine.

Fourth, to provide an improved paper making machine in which there is little likelihood of breakage in the web and consequent loss of time and material even when manufacturing very thin paper.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing, forming a part of this specification, in which:

Figure I is a diagrammatic and conventional illustration of parts of a paper making machine of the Harper-Fourdrinier type embodying the features of my invention.

Fig. II is a diagrammatic and conventional illustration of a paper making machine of the cylinder type embodying the features of my invention.

In the drawing similar reference characters refer to similar parts in both views.

In the drawing, 1 represents the head box of a paper making machine from which the pulp flows to the making wire 2 supported by the breast roll 3 at one end and couch roll 4 at the other. 5 represents the deckle straps for regulating the width of the

web. Other parts of the paper making machine proper are not illustrated as such features form no part of my invention and machines of the Harper-Fourdrinier type are well known in the art.

6 represents the web, which is transferred from the making wire to press felt 7 supported at its front end by the couch roll 8. This press felt extends to and delivers the web to the first cylinder 9 of the drier. The press felt is supported and guided by suitable rolls. I refer specifically only to such of these as are of importance on account of their coacting relations to other parts.

The press rolls 10 and 11 are located between the couch roll 8 and first drying cylinder 9 and the forward reach of the press felt passes between them, being supported over the upper press roll 10 by roll 12 and carried reversely therethrough over the guide roll 13. A guide roll 14 is disposed below the lower press roll. From the guide roll 14 the felt passes over the roll 15 which is positioned above the first drying cylinder. From thence it passes over the roll 16 which is supported so that the felt is held in contact with the drying cylinder as it passes over this roller, the roller constituting a smoothing roll for the web.

I pass the return reach of the felt through a washing tank 17 and the wringer rolls 18. The felt is passed through the tank in a series of loops and sprays 19 deliver there against as the felt leaves the tank and passes to the wringer or squeeze rollers.

I provide a second or take off felt 20 which is supported on suitable guide rolls to pass between the press rolls with the press felt. The felt 20 is provided with a suitable tensioning device as 21. One of its guide rolls 22 is positioned so that this second felt engages the web as it passes over the press felt guide roll 13. The felt 20 is passed over the roll 14 so that the web is held to the press felt as it passes from the press rolls. On its return reach the felt 20 is carried through a second washing tank 17, the tank illustrated being a duplicate of that described for the press felt. The press roll 10 is preferably a suction roll.

In the embodiment shown in Fig. II, 23 represents the pulp tank and 24 the making cylinder from which the web is delivered to the press felt 7, the remaining parts being arranged substantially as has been described.

With this arrangement of parts I am able to successfully manufacture tissues and other light thin papers rapidly and with little likelihood of breaking the web as it 5 passes through the press rolls or as it is delivered to the drier. The web is supported continuously from the couch roll 8 to the first drying cylinder and is held against the drying cylinder throughout a substantial arc 10 of the cylinder until it becomes considerably dried and is of such strength as to pass to the second drying cylinder without likelihood of breakage.

Another advantage of my construction is 15 that it makes it practical to use inferior press felts than has heretofore been used, thereby giving longer life to the felt. The arrangement further permits the continuous washing of the felts and the use of a suction 20 roll as one of the press rolls.

While my improvements are particularly desirable for use in the manufacture of tissue and light papers they are also desirable for use in the manufacture of heavier papers. I have shown my improvements merely in diagrammatic or conventional form as I believe the same will be readily understood and embodied, from such illustrations, by those skilled in the art to which 25 30 my invention relates as the particular machine to which it is adapted and its surroundings may require.

Having thus described my invention, what I claim as new and desire to secure by 35 Letters Patent, is:

1. In a paper making machine, the combination with a couch roll, press rolls and a drying cylinder, of a press felt extending from said couch roll to said drying cylinder 40 to discharge the web thereto with its forward reach passing between said press rolls, one of said rollers being a suction roll, there being a pair of guiding and supporting rolls for said press felt positioned adjacent 45 said press rolls and so that the press felt is carried over and reversely between said press rolls, a pair of rolls positioned adjacent said drying cylinder supporting said press felt in contact with a substantial arc 50 thereof, the second of such rolls constituting a smoothing roll and being positioned so that the press felt is held to the drying cylinder as it passes over the roll, a second felt guided to and passing between said press rolls to engage the under side of the web and hold 55 it to said press felt after it leaves the press rolls, and washing means for said felts disposed so that the felts are washed on their return reaches.

2. In a paper making machine, the combination with a couch roll, press rolls, and a drying cylinder, of a press felt extending 60 from said couch roll to and into contact with

said drying cylinder to discharge the web thereto with its forward reach passing between said press rolls, one of said rollers being a suction roll, there being a pair of guiding and supporting rolls for said press 70 felt positioned adjacent said press rolls and so that the press felt is carried over and reversely between said press rolls with the web on the under side thereof, and a second felt guided to and passing between said press 75 rolls, and over the said guiding and supporting roll at the rear thereof, in engagement with the under side of the web.

3. In a paper making machine, the combination with a couch roll, press rolls, and a drying cylinder, of a press felt extending from said couch roll to said drying cylinder and into contact therewith to deliver the web thereto with its forward reach being guided to and passing between said press 80 rolls, with the web on the under side thereof, a pair of rolls positioned adjacent said drying cylinder supporting said press felt in contact with a substantial arc thereof, the second of such rolls constituting a smoothing 85 roll and being positioned so that the press felt is held to the drying cylinder as it passes over the roll, a second felt guided to and passing between said press rolls to engage the under side of the web and hold 90 it to said press felt after it leaves the press rolls, and washing means for said felts disposed so that the felts are washed on their return reaches.

4. In a paper making machine, the combination with a couch roll, press rolls, and a drying cylinder, of a press felt extending from said couch roll to said drying cylinder and into contact therewith to deliver the web thereto with its forward reach guided to 100 and passing between said press rolls, with the web on the under side thereof, a second felt guided to and passing between said press rolls to engage the under side of web 105 and hold it to said press felt after it leaves the press rolls, and washing means for said felts disposed so that the felts are washed on their return reaches.

5. In a paper making machine, the combination with press rolls, and a drying cylinder, of a press felt with its forward reach guided to pass between said press rolls, with the web on the under side thereof, said felt being reversed at the rear of said press rolls to bring the web to the top side thereof, and extending to and held into contact with said drying cylinder to deliver the web thereto, a pair of rolls positioned adjacent said drying cylinder supporting said press felt in contact with a substantial arc thereof, the second of such rolls constituting a smoothing 110 roll and being positioned so that the press felt is held to the drying cylinder as it passes over the roll, and a second felt engaging 115 the under side of the web, passing be- 120

tween said press rolls to hold the web to said press felt after it leaves the press rolls.

6. In a paper making machine, the combination with press rolls, and a drying cylinder, of a press felt with its forward reach guided to and passing between said press rolls with the web carried thereby on its under side, said press felt extending to and being held in contact with said drying cylinder to deliver the web thereto, and a second felt passing between said press rolls and

guided and supported to engage the under side of the web to said press felt after it leaves the press rolls.

In witness whereof I have hereunto set my 15 hand and seal in the presence of two witnesses.
